UNITED STATES PATENT OFFICE.

O. O. FURBUSH, OF MACHIAS, MAINE.

APPARATUS FOR DELIVERING PAPER FROM PRINTING-PRESSES.

Specification forming part of Letters Patent No. 47,411, dated April 25, 1865.

To all whom it may concern:

Be it known that I, O. O. FURBUSH, of Machias, in the county of Washington, in the State of Maine, have invented a new and Improved Machine for Delivering Paper from Printing-Presses; and I do hereby declare that the following is a full, clear, and exact description thereof, which will enable others skilled in the art to make and use the same, reference being had to the accompanying drawings, making part of this specification, in which—

Figure 1 is a side sectional view of my invention, taken in the line α α , Fig. 2; Fig. 2, a plan or top view of the same.

Similar letters of reference indicate like parts.

This invention consists in the employment or use of nippers arranged in such a manner as to have a reciprocating motion to convey the sheets from the press.

A represents a rectangular frame, in the upper part of which two rollers, B B, are placed transversely and around which endless belts C C pass. To these belts a bar, D, is attached transversely, the ends of the latter being fitted in grooves α in the sides of the frame, which serve as guides for said bar.

E is a bar which is connected to the bar D by hinges b, the latter being at the under side of the bars to admit of the bar E turning downward, the ends of the latter having no connection with the frame A. The bar E is, when not actuated so as to be turned or forced downward, kept in a horizontal position with the bar D by means of an india-rubber or other spring F, attached to the upper surfaces of said bars.

To the bar D there are attached two or

more metal strips, c, which form one jaw of nippers G, the other jaw, d, being attached to the bar E. The jaws of these nippers, when the bar E is in a horizontal position with the bar D, are in contact, and they are separated when the bars D E reach either end of the frame A, in consequence of pins e, which project laterally from pendent blocks f, attached to the ends of the bar E, passing underneath beveled projections g at the sides of the frame A, which cause the bar E to turn downward and the jaws of said bars to move upward from the jaws.

The nippers G have a reciprocating motion given them by operating or turning one of the rollers B first in one direction and then in the other, the sheet being received by the open jaws when the latter are at the back end of the frame near the press, the jaws closing and grasping the sheet as they move toward the opposite or outer end of the frame, the jaws opening when they reach said end, so that the sheet may be withdrawn from them.

I do not claim, broadly, the advancing and receding opening and closing nippers; but

What I claim as new, and desire to secure by Letters Patent, is—

The bars D E, provided, respectively, with jaws c d, the projection f, and pin e, in combination with inclined planes g g, the spring F, and the bolt C, by which the jaws are opened and closed at the appropriate times to receive, clasp, convey, deliver, and return, substantially as above described and represented.

C. O. FURBUSH.
